UNITED STATES PATENT OFFICE.

JAMES H. DAVIS, OF CHICAGO, ILLINOIS, ASSIGNOR TO AMERICAN ENGINEERING SPECIALTY CO., OF CHICAGO, ILLINOIS, A CORPORATION OF ILLINOIS.

THERMOSTATIC VALVE.

No. 836,636.

Specification of Letters Patent.

Patented Nov. 20, 1906.

Application filed March 29, 1904. Serial No. 200,653.

To all whom it may concern:

Be it known that I, JAMES H. DAVIS, a citizen of the United States, residing at Chicago, in the State of Illinois, have invented 5 certain new and useful Improvements in Thermostatic Valves, of which the following is a specification.

My invention relates to means for automatically opening and closing a valve dependent 10 upon the temperature of the fluid flowing through the same. The objects of the invention are, to provide such a valve with increased sensibility to the changes of heat in the passing fluid; to provide a valve in which both the valve seat and the valve proper 15 move under the influence of the increased heat; to provide a superior form of valve having compensating means allowing yielding of the valve on its stem after seating; to 20 make a more accurate and positive operating valve for the purpose, and to generally improve the structure and operation of thermostatic valves. These objects, together with other advantages which will hereinafter appear, I attain by means of the construction 25 illustrated in preferred form in the accompanying drawings, wherein—

Figure 1 is a vertical section through one form of my improved thermostatic valve, 30 showing the valve open;

Figure 2 is a horizontal section on the line 2, 2, of Figure 1;

Figures 3 and 4 are respectively a top plan and a side elevation, of a form of spring to 35 allow yielding of the valve as it is pressed to its seat;

Figure 5 is a vertical central section through a modified form in which the valve is outside 40 of the tubular casing carrying the valve seat, and

Figure 6 is a horizontal section on line 6, 6, of Figure 5.

In the structure as illustrated in Figures 1 to 4, it will be seen that I have provided a 45 casing 7 which is attached to the steam pipe 8 and carries an upwardly extending cylinder which is closed by a screw cap 10, and supports the screw adjusted head 11 carrying the valve stem 12. The stem 12 has at its 50 bottom a head 13 and an elongated shank extended downward therefrom which is surrounded by the valve disk 14 and the head and the valve proper are separated by a

spring 15 which in preferred form is shown more clearly in Figures 3 and 4. This spring 55 is preferably made of a disk with spurs 15^a punched out and projecting below as shown in Figure 4, making a spring which bears upon the valve at several independent points.

The valve proper, 14, is surrounded by a 60 valve seat 16 formed in the lower end of a tubular support 17, and this tube at its top has an annular flange 18 resting upon the cylinder 19, this latter being supported upon a series of lugs 20 made integral with the outside 65 casing 9 as appears in Figure 1. I prefer to make the casing 9 and tube 17 of iron, while the valve stem 12 and the supporting cylinder 19 are of brass.

It will be seen from this construction that 70 when the steam enters the chamber so as to act upon the various parts thereof, when the temperature rises too high the expansion of the long valve stem 12 downward will press the valve upon its seat, and at the same time 75 the expansion of the cylinder 19 will raise the tube 17 carrying the valve seat, upward, so that there is a double sensitiveness of movement and a quick action, the valve and seat moving toward each other to close the valve. 80 After the valve has come in contact with its seat further movement of the parts toward each other may be compensated for by the yielding of the spring 15 between the valve and the head 13. On the other hand, by the 85 cooling of the device the reverse action takes place, that is the contraction of the stem 12 and the cylinder 19 cause the valve and its seat to move away from each other, opening the valve and admitting the steam 90 again. The action is the same whether the steam flows through the parts as illustrated in Figure 1 or in the inverse direction as in Figure 5.

In Figure 5 I have illustrated a modification in which the valve is outside the tube carrying the valve seat. In this case the cylinder 19^a rests upon the lugs 20 carried in the brass casing 9 and supports the head 18 of the brass valve seat tube 17. The valve seat in this case is on the outer end of the tube and the iron valve stem 12 extends through the tube and carries on its lower end the valve 14 supported upon the stem with spring 15 by means of the nut 13^a as will be apparent 105 from Figure 5. In this instance it will be

seen that the expansion of the cylinder 17 downward will move the valve seat toward the valve at the same time that the expansion of the outer casing 9 upward will by 5 means of the head 11 lift the valve stem 12 and draw the valve 14 toward its seat, thus again making a double movement of the valve and seat and giving superior sensibility and rapidity of action.

10 It will be noted that by the valve proper being carried upon an adjustable head the distance of the valve from its seat may be regulated as desired. It will be understood of course that a coil or any other form of 15 spring may be used instead of the peculiar spring 15 which I have used herein, but I regard this as superior for the purposes as it engages the valve at three points of contact, and keeps it adjusted properly to fit its seat, 20 while at the same time a spring of very great resistance may be provided in very small space. Other advantages of the device will readily occur to those familiar with the art.

Having thus described my invention and 25 illustrated its use, what I claim as new, and desire to secure by Letters Patent, is the following:

1. In a thermostatic valve, the combination of a closed casing provided with an inlet 30 and an outlet and composed of a material having a low coefficient of expansion, a valve suspended therein having a stem composed of a material having a high coefficient of expansion attached to the top of the casing and 35 controlling the inlet to the casing, and a tube composed of a material having a low coefficient of expansion having therein a valve seat, mounted upon a supporting tube of a material having a high coefficient of expansion 40 said supporting tube being supported by the casing, whereby the valve and seat move together when the entering steam heats the expansible elements, substantially as described.

45 2. In a thermostatic valve the combination of a casing having therein a valve stem of a material having a high coefficient of expansion and a valve on the stem, a supporting tube in the casing of a material having a

high coefficient of expansion, a valve seat 50 supporting tube suspended on said first tube and composed of a material having a low coefficient of expansion, and resilient means interposed between the valve and the stem which allows for extra play of the valve 55 after the valve has met its seat, substantially as described.

3. In a thermostatic valve, a casing provided with a series of projecting lugs, in combination with a loose supporting cylinder of 60 a material having a high coefficient of expansion resting upon said lugs, a tube of a material having a low coefficient of expansion suspended therein and supporting the valve seat, and a valve to coöperate therewith.

4. The combination in a thermostatic valve, of a casing provided interiorly with a series of lugs, a valve stem of a material having a high coefficient of expansion adjustably 70 mounted therein, a cylinder of a material having a high coefficient of expansion supported on the said lugs and a tube of a material having a low coefficient of expansion carrying a valve seat and supported upon 75 said cylinder.

5. In a thermostatic valve, the combination of an iron casing carrying therein a brass valve stem, and provided with a series of supporting-lugs, a brass expansion ring seated 80 upon said lugs, and an iron tube carrying a valve seat resting upon said expansion ring.

6. In a thermostatic valve, the combination with a valve casing and an extended expansion casing having a screw cap thereon, 85 of a tube supported at its top adjacent the cap carrying a valve seat at its base, and a stem in the tube carrying a valve, all parts mounted in said casing, and removable through the cap of the casing, substantially 90 as described.

In testimony whereof I have hereunder signed my name in the presence of the two subscribed witnesses.

JAMES H. DAVIS.
